CLAIM

The ornamental design for a supporting arm for television receiver as shown and described.

DESCRIPTION

1. Supporting arm for television receiver

1.1 : Perspective

1.2 : Back perspective view

1.3 : Front

1.4 : Back

1.5 : Left

1.6 : Top

1.7 : Bottom

The claimed design is a supporting arm for television receiver integrated with a case; the characteristic features of the design lie in the shape; the broken lines indicate portions of the article that form no part of the claimed design; the right side view is omitted because it is a mirror image of the left side view, reproduction 1.5; the appearance of any part

(Continued)

of the article not shown in the drawings or described in the specification forms no part of the claimed design.
